GEORGE F. HANDLEY, OF GLENDALE, NEW YORK, ASSIGNOR, BY MESNE ASSIGNMENTS, TO ROYAL TYPEWRITER COMPANY, INC., OF NEW YORK, N. Y., A CORPORATION OF NEW YORK.

CARD GUIDING AND HOLDING DEVICE FOR TYPE-WRITING MACHINES.

1,121,829.

Specification of Letters Patent. Patented Dec. 22, 1914.

Application filed July 19, 1912. Serial No. 710,355.

To all whom it may concern:

Be it known that I, GEORGE F. HANDLEY, a citizen of the United States of America, residing in Glendale, Long Island, county 5 of Queens, and State of New York, have invented a certain new and useful Improvement in Card Guiding and Holding Devices for Type-Writing Machines, of which the following is a specification.

10 This invention comprises an improvement upon structures heretofore invented by Edward B. Hess.

It relates more particularly to card guiding and holding devices for visible writing 15 machines and to a special style of means, of the class in which there is a card guide that serves to direct an inserted card or sheet from front feed rolls, and devices extending upwardly across the printing line, said devices comprising a card guiding and holding finger that extends across the line of print adjacent the printing point and is pivoted so that it may be depressed from in front of the printing line when desired. 20 When in elevated operative position, it is positively locked against lateral strains in either direction and when depressed remains in normal lowered position until raised by the operator.

25 The invention relates particularly to a novel means for locking the guide finger in elevated position and for tripping it for return to depressed condition as will herein-after appear in detail.

30 The invention is indicated as applied to a Royal Standard front strike visible writing machine.

In the accompanying drawing: Figure 1 is a partial front elevation indicating the 35 platen, the shift rail, the card guiding and holding devices and related parts; Fig. 2, a vertical transverse section; Fig. 3, a detail front elevation; Fig. 4, a detail elevation of a minor feature of the construction; Fig. 45 5, a perspective view of a re-action spring adapted to be applied to the card holding finger; Fig. 6, a detail front elevation showing a modification; and Fig. 7 is a detail plan view showing left hand movable card holding finger and associated parts.

50 1 represents the ordinary shift rail; 2, the bottom rail of the transversely movable frame in which is mounted the rotatable platen, and 4 indicates bearing balls inter-

posed between the bottom rail of the platen 55 frame or carriage and the shift rail. Ordinary rear feed rolls are marked 5 and the front feed rolls 6. On the top face of the shift rail by means of a horizontal foot 7 is bolted an upwardly extending plate 8 that 60 is shaped to project forwardly and then extends upwardly in a plane somewhat in front of the front printing face of the platen. Below the platen, however, the plate is bifurcated into two arms 9, 10 which first 65 extend laterally and then vertically. Between these two arms is mounted the ordinary type bar guide 11 and ribbon vibrator 12. Extending horizontally between the upper portions of the guide arms 9, 10 is a scale 70 plate 13 disposed at or closely adjacent the lower line of print and which may be adjustable as disclosed in the patent to Edward B. Hess No. 950,326, dated February 22, 1910. Such adjustment is indicated in 75 Fig. 4 in which there is shown beneath the bolt head, in dotted lines, a square aperture 38 in arm 9 and in the center a small dotted circle 39 indicating the shank of the securing screw. The scale is notched at the 80 middle for the passage of type bars 14 to the printing point and at its ends outside of the upright card arms 9, 10 it is flared outwardly and curled to avoid projecting sharp edges. A prolongation of the arm 10 of the 85 scale is in the form of a somewhat tapered finger 15 curved in the direction of the circumference of the platen and also somewhat in a direction longitudinally of the platen, the effect being to throw its side edges 16 90 forwardly. The paper guiding and holding finger so shaped, or of other suitable shape and constructions, lies somewhat closely contiguous to the platen surface and holds and directs cards that are fed up from the front 95 feed rolls and that are guided by the arms 9, 10. This general arrangement together with a co-operating bail rod 17 carried in the ends of pivoted arms 18 and having rollers 19 thereon co-operating with the surface of 100 the platen above the line of print and beyond the line in which the ends of the guide finger 15 terminates are all old prior to my invention. There is a similar guide finger disposed at the upper end of the guide arm 105 9. One or both of these may be pivoted so that they may stand in normal operative position or be depressed from in front of the

line of print. It is sufficient to show one of them as pivoted and ordinarily only the one to the left of the printing point need be so arranged.

- 5 Extending laterally from the upper end of the arm 9 adjacent the point at which the scale 13 is attached to it is an integral plate 20 which adjacent the arm 9 is bent or deflected so as to extend forward at an oblique angle to the axis of the platen as at 20'. Upon this obliquely disposed plate 20 is pivoted the finger 15^x which is formed with an extension 22 at right angles thereto and this extension is formed with a cam 15 enlargement 23 that lies flat against the obliquely projecting plate 20 and is pivoted on a stud bolt 24 rigidly fixed in the plate. The finger 15^x is with respect to its extension 22, 23 set at such an angle that when 20 in elevated position it stands opposite the front face of the platen in the same relation thereto as does the fixed finger 15^x. Pivoted on a downward extension 25 from the obliquely disposed part 20' of plate 20 is a 25 spring latch 26 provided with a finger piece 27. A coiled spring 28, surrounding the stud bolt 24 has one end hooked under the latch 26 and the other hooked around the edge of extension 22 forming part of the finger 15^x. The reaction of this spring tends 30 to depress the guide finger to the position shown in Fig. 3 in which a shoulder 29 on the base portion of the finger 15^x rests against an upwardly extending lug 30 on the latch 26. From the shoulder 29, the 35 base plate of the guide finger is formed with a circular edge 31 of suitable radius terminating in a second radial shoulder 32.
- 40 The operation is as follows: Assuming the guide finger to be depressed as in Fig. 3, the operator lifts it to elevated position indicated in Fig. 1 in which the shoulder 32 passes over the end of latch projection 30, the result being that the finger is locked in 45 operative position against any strain tending to move it to the left. At the same time, the horizontal base edge 15' forming the lower edge of the guide finger proper lies against the straight horizontal upper 50 edge of the guide arm 9 so that the guide finger is locked in operative position against strains tending to throw it to the right. Such strains exerted in either direction 55 may arise because of engagement of the finger 15^x with the edge of an inserted sheet or card traveling transversely with the platen. When it is desired to have the guide finger depressed below the line of print, it is only necessary to depress the 60 finger piece of latch lever 26 and the projection 30 thereon passes out of engagement with shoulder 32 when reaction of spring 28 throws the guide finger downwardly into inoperative position as in Fig. 65 3. The strain required to raise the guide

finger to operative position is very slight. It is only required to overcome reaction of spring 28, and yet the finger is positively locked in elevated position. A slight depression of the spring latch trips the finger 70 and allows the spring to throw it to lowermost position. In either movement of the guide finger therefore no strain is imposed upon the arms 9, 10 and associated parts. This is an advantage not only because such 75 parts are light and should not be subject to material strains but in addition to that the amount of exertion required of the operator is trivial.

Fig. 6 shows a modification. The general 80 behavior and construction is quite analogous to what has been described there being however this distinction. The tripping latch 33 is generally horizontal and is pivoted at 34 intermediate its ends upon an extension of 85 the obliquely disposed plate part 20 extending from arm 9. The base portion 35 of the guide finger 15^x is formed with a substantially radial shoulder 36. The reaction spring 37 is applied substantially as already 90 described being turned around the stud bolt 24 and having one end hooked over the base portion of the guide finger above the stud bolt and the other under the lever between its axis and latch end. 95 When the guide finger is in elevated position shown in Fig. 6 lifting of the outer end of the tripping lever will disengage the latch upon its inner end from the shoulder on the base extension of the guide finger thereby allowing the reaction spring to throw the guide finger to depressed position. A slight lifting strain exerted by the finger of the operator upon the finger 15^x restores the 100 parts to position as seen in Fig. 6 in which the guide finger is positively locked against lateral strains exerted in either direction.

I have stated already that this invention is an improvement upon the structures heretofore devised by Edward B. Hess and I 110 do not therefore claim the pivoted guide finger turning in a plane oblique to the axis of the platen and having applied thereto a spring that tends to retract it from elevated position in connection with means for 115 positively locking the guide finger against lateral strains in either position when it is elevated.

The form of the invention preferred is that indicated in Figs. 1, 2 and 3 since it is 120 deemed to be more convenient for the operator to drop a finger upon the finger piece of the latch lever rather than to lift the free end of the latch lever as is required of the construction indicated in Fig. 6.

I claim:

1. A paper guiding card holding finger adapted to occupy two positions in one of which it extends across the line of print and in the other of which it is depressed, a sup- 130

port upon which the guide finger is pivoted, said guide finger being provided with a shouldered edge, a tripping latch lever directly engaging said shoulder and a reaction spring tending, when the latch is tripped, to throw the guide finger from elevated to depressed position.

2. A card holding and guiding finger adapted to occupy two positions in one of which it extends across the line of print and in the other of which it is depressed from the line of print, said guide finger having a base extension, a support upon which it is pivoted, two radial shoulders in such base extension and a reaction spring tending to throw the guide finger from elevated to depressed position and a tripping latch that engages one of said shoulders to limit downward movement of the guide finger and the other of said shoulders to positively lock the guide finger in elevated position.

3. A card guiding and controlling finger adapted to occupy a position in which it extends across the line of print and also a position in which it is lowered from the line of print, said finger being provided with a base extension, a support upon which such base extension is pivoted, a reaction spring tending to throw the guide finger from ele-

vated to lowered position and a downwardly movable detent latch adapted to positively lock the guide finger in elevated position.

4. A card guiding and controlling finger adapted to occupy two positions, in one of which it lies across the line of print and in the other of which it is lowered from the line of print combined with an upright card guiding arm having a lateral extension adjacent its top, a base extension forming part of the card guiding finger and by means of which it is pivoted to said lateral extension from the card guiding arm, a tripping latch also pivoted upon said lateral extension and a spring applied to the latch and also to the guide finger and a projection of the base extension of the guide finger co-operating with the latch whereby when the latch is manipulated the guide finger is tripped and the spring allowed to throw it to lower position but when the finger is elevated the base is locked with the finger in operative position.

In testimony whereof, I have hereunto subscribed my name.

GEORGE F. HANDLEY.
